UNITED STATES PATENT OFFICE.

GEORGE OLDHAM AND WILLIAM DIXON, OF PHILADELPHIA, PA.

LOOM FOR CROSS-WEAVING.

SPECIFICATION forming part of Letters Patent No. 352,258, dated November 9, 1886.

Application filed March 9, 1886. Serial No. 194,709. (No model.)

To all whom it may concern:

Be it known that we, GEORGE OLDHAM and WILLIAM DIXON, both of Frankford, Philadelphia, in the county of Philadelphia and 5 State of Pennsylvania, have invented a new and useful Improvement in Looms for Cross-Weaving, of which the following is a full, clear, and exact description.

Our invention relates to looms for weaving 10 warp into filling-threads for making chenille, rugs, mosquito - netting, or any other cross-woven fabric; and the invention consists, principally, of means for giving the heddles lateral horizontal movement for crossing the 15 warp-threads between the strands of filling.

The invention also consists of the special construction of the harness or plates that carry the warp-threads; and the invention finally 20 consists of the construction, arrangement, and combination of parts, all as hereinafter described and claimed.

Reference is to be had to the accompanying drawings, forming a part of this specification, in which similar letters of reference indicate 25 corresponding parts in all the figures.

Figure 1 is a front elevation of a simple form of our improvement for making narrow fabric with two sets of harness-plates, without warp-beam, lay, or shuttle movement. 30 Fig. 2 is a transverse sectional elevation of the same, taken on the line $x-x$ of Fig. 1. Fig. 3 is a sectional plan view taken on the line $y-y$ of Fig. 1. Fig. 4 is a similar view taken on the line $z-z$ of Fig. 1. Fig. 5 is an enlarged perspective view of two of the harness- 35 plates and warp-threads passing through the eyes of the same. Fig. 6 is an end view of the cam-shaft for laterally reciprocating the heddles.

The frame shown is composed of the two side pieces, $a a$, base b , and top cross-piece, c , on the under surface of which latter are attached brackets for the roller d , over which the cords or straps $e e$ pass, to the ends of 45 which cords or straps the heddles $f f$ are attached. The heddles are guided at each end by staples $g g$, passing around the upright rods $h h$, and are adapted to be alternately reciprocated by the levers $i i$, pivoted at j to the 50 base b , and connected to the heddles by the

cords or connecting-rods $k k$. The upright rods $h h$ at each end of the heddles are connected together at their upper and lower ends by plates or cross-pieces $l l$, and these plates or cross-pieces $l l$ are centrally pivoted to the 55 horizontal supports or arms $m m$, forming in this instance a part of the upright plates $n n'$, secured to the inner surface of the side pieces, $a a$, of the main frame. In a cross-brace, o , is journaled the horizontal shaft p , contiguous 60 to one of the plates l , which shaft is formed with opposite cams, $p' p'$, at its ends, so that the shaft when revolved will cause the cams $p' p'$ to act alternately against the ends of the plate l and vibrate it, and through it and the 65 rods $h h$ and the other plates, l , reciprocate the heddles $f f$ laterally and horizontally at the same time they are reciprocated vertically, which causes the harness-plates $q q$ to cross the warp-threads $r r$ over the filling-threads 70 and to twist them together or cross them between the filling-threads.

The cam-shaft p is revolved intermittently by the ratchet-wheel s , secured to one end of the shaft, and the pawl s' , pivoted to the plate 75 s^2 , which is pivoted at one end upon the shaft p near the ratchet-wheel s , and connected at its other end to the plate t , attached to the front heddle, so the up-and-down movement of the heddle vibrates the plate s^2 and causes 80 the pawl to turn the shaft p at each upward movement of the heddle. The plate s^2 is connected to the plate t , in this instance, by the pin t' entering a slot, t^2 , made in the plate t , to accommodate the lateral movement of the 85 heddle.

The harness-plates q are made of thin pieces of metal, each formed with an eye, q' , through it for the warp-thread, and each beveled at its end near the eye, as shown at q^2 , to form an 90 angle to bring the passing points as near together as possible, as shown in Fig. 5. The eyes q' are formed by making an orifice through the harness-plates and bending the stock on each side of the orifice in opposite directions, 95 as shown at $q^3 q^4$, to permit the warp-thread to pass in a straight line through the eye, and so there will be little or no friction of the warp in the eyes.

Having thus fully described our invention, 100

we claim as new and desire to secure by Letters Patent—

1. The heddles *f*, the vertical rods *h*, to which the heddles are loosely attached, the plates *l*, in which the rods *h* are held, the supports *m* for the plates *l*, the latter being pivoted centrally to said supports, and the frame to which the supports are attached, in combination with the cam-shaft *p* and means, substantially as described, intermediate of said cam-shaft and one of the heddles, for actuating the cam-shaft, substantially as set forth.

2. The heddles *f*, the vertical rods *h*, on which they are placed, the centrally-pivoted plates *l*, that hold the said rods, the supports *m* for the plates *l*, and the main frame, to which the supports *m* are attached, in combination with

the cam-shaft *p*, the ratchet *s*, the pawl *s'*, the lever *s''*, the plate *t*, and the pin or stud *t'*, substantially as set forth.

3. The heddle-plate *q*, formed with the eye *q'*, made near the end of the plate and in line with the width of the plate by curving the stock in opposite directions from a central slot, the point of the plate being beveled at *q''* from the outer edge entirely across the plate to the inner edge thereof, substantially as described.

GEORGE OLDHAM.
WILLIAM DIXON.
